AUTOMOBILE WITH REARWARDLY OPENING ENCLOSED LUGGAGE CARRIER

Max L. Wymore, 3441 S. Ivy Way,
Denver, Colo. 80222

Filed Aug. 4, 1965, Ser. No. 86,436

Term of patent 14 years

(Cl. D14—3)

FIG. 4.

FIGURE 1 is a side elevational view of an automobile with rearwardly opening enclosed luggage carrier showing my new design;

FIGURE 2 is a rear elevational view thereof on a larger scale;

FIGURE 3 is a top plan view thereof showing the door of the carrier in open position above the tailgate of the station wagon, portions of which are broken away to conserve space;

FIGURE 4 is a front elevational view thereof on a larger scale.

The side opposite that appearing in FIGURE 1 is a mirror image of that shown.

This is a continuation-in-part of design application Serial No. D.81,485, filed August 28, 1964, and now abandoned.

I claim:

The ornamental design for an automobile with rearwardly opening enclosed luggage carrier, as shown and described.
